UNITED STATES PATENT OFFICE

117,972

DESIGN FOR A DUST COLLECTING APPARATUS

Eugene A. Failmezger, De Witt, N. Y., assignor to United States Hoffman Machinery Corporation, New York, N. Y., a corporation of Delaware

Application April 19, 1939, Serial No. 84,393

Term of patent 14 years

To all whom it may concern:

Be it known that I, Eugene A. Failmezger, a citizen of the United States, residing at De Witt, in the county of Onondaga and State of New York, have invented a new, original, and ornamental Design for a Dust Collecting Apparatus, of which the following is a specification, reference being had to the accompanying drawing, forming part thereof.

Fig. 1 is a rear perspective view of a dust collecting apparatus showing my new design; and Fig. 2 is a front perspective view thereof.

I claim:

The ornamental design for a dust collecting apparatus, as shown.

EUGENE A. FAILMEZGER.
